UNITED STATES PATENT OFFICE.

JOHN E. CARROLL, OF PHILADELPHIA, PENNSYLVANIA, ASSIGNOR TO CO-2 PRODUCTS COMPANY, OF PHILADELPHIA, PENNSYLVANIA, A COMPANY EXISTING UNDER A DECLARATION OF TRUST.

VENDING MACHINE FOR COMPRESSED GASES AND FLUIDS IN CONTAINERS.

Application filed June 21, 1923. Serial No. 646,808.

To all whom it may concern:

Be it known that I, JOHN E. CARROLL, a citizen of the United States, residing at 1919 North 11th Street, Philadelphia, in the county of Philadelphia and State of Pennsylvania, have invented new and useful Improvements in a Vending Machine for Compressed Gases and Fluids in Containers, of which the following is a specification.

10 My invention relates to new and useful improvements in a vending machine for compressed gases and fluids in containers, and has for its primary object to provide an apparatus which will deliver a full container upon insertion of a coin and an empty container and the proper manipulation of the operating handle.

Another object of this invention is to produce a vending apparatus wherein the 20 use of springs, gears and racks or similar appurtenances are eliminated.

A further object of my invention is to provide a plurality of rotary carriers, alternate ones of which move in opposite directions, to assist in conveying containers intermittently over suitable supports and cause one on each support to drop through a hole to the next support when one is delivered and another inserted.

30 With these ends in view, this invention consists in the details of construction and combination of elements hereinafter set forth and then specifically designated by the claims.

35 In order that those skilled in the art to which this invention appertains, may understand how to make and use the same, I will describe its construction in detail, referring by numerals to the accompanying drawings 40 forming a part of this application, in which:

Fig. 1 is a vertical sectional view of the vending machine embodying my invention with portions left in elevation and the lock 45 illustrated with relation to the other parts.

Fig. 2 is a top plan view of the device with a portion broken away to show a detail of construction and illustrating in dotted lines the position of the hole in the ring plate or cover when the machine is closed.

Fig. 3 is a sectional side elevation of the top, ring plate, and ring plate actuating mechanism.

Fig. 4 is a fragmentary sectional view at

the line 4—4 of Fig. 1 with the top removed and a part of the ring plate or cover broken away.

Fig. 5 is an edge view of the ring plate or cover.

Fig. 6 is a fragmentary sectional plan view at the line 6—6 of Fig. 1 with the circular partitions removed.

Fig. 7 is a similar view at the line 7—7 of Fig. 1.

Fig. 8 is a plan or face view of the compound lever.

Fig. 9 is a plan view of the uppermost carrier and its support.

Fig. 10 is a section at the line 10—10 of Fig. 9.

Fig. 11 is a plan view of the carrier and support just below the uppermost one and positioned relative thereto.

Fig. 12 is a section at the line 12—12 of Fig. 11.

Fig. 13 is a plan view of a third carrier and support which is arranged below the second one and is positioned relative to the others.

Fig. 14 is a section at the line 14—14 of Fig. 13.

In carrying out my invention as herein embodied, 15 is the lowermost of a plurality of supports and forms the bottom of the machine. This support is provided with legs 16 in order that it shall be suitably elevated above the surface or object on which the machine rests. Around the outer edge is an integral upstanding flange 17 and concentric therewith is an annular rib 18 forming a raceway between it and the flange 17 and through the support within the raceway is formed a hole 19, Figs. 13 and 14, which acts as the exit for the delivery of a container.

In the center of the support 15 is formed a boss 20 in which is journalled the lower end of the vertical operating shaft 21, the latter being enclosed by a central tube or hollow column 22 fixed to the rib 18.

To the upper end of said tube or column is fixed a ring 23 including concentric inner and outer walls 24 and 25 respectively with a groove 26 between them. The upper or outer edge of the outer wall coincides with the upper end of the tube 22 while the inner wall 24 projects above the outer wall and tube so as to form a rest for the top 27

which has a rib 28 telescoping within the ring 23.

The top has a hole 29, Fig. 2, which acts as the entrance for the insertion of empty containers, and a coin slot 30 in alignment with the groove 26 from which latter leads a coin slot 31 in staggered relation to the slot 30. On the outer edge of the top rests a portion of the casing 32 which encloses the parts of the machine and is detachably connected with the flange 17 of the bottom support 15.

Underneath the top 27 and within the confines thereof is located a ring plate or cover 33 resting upon the upper end of the tube 22 and outer wall 25 of the ring 23 while surrounding the inner wall 24 of said ring so as to rotate thereabout. This ring plate or cover has a coin notch 34 in its inner edge, Fig. 4, adapted to be moved into registration with either of the coin slots 30 in the top or 31 in the ring 24 and is also provided with a hole 35 adapted to be moved into registration with the hole 29 in the top.

The upper end of the operating shaft 21 projects through the top and has fixed thereon a handle 36 for actuating it while on said shaft below the cover is fixed a coin pushing finger 37 projecting through suitable slots in the rib 28 and inner wall of the ring 23 and operating between the top and ring plate so as to engage a coin dropped into the slot 30 and for coaction with said finger is a lip 38 formed with the ring plate or cover and produced by partially cutting a section of metal from the plate and bending the same upward or outward as plainly shown in Fig. 5.

From the foregoing it may be seen that when a coin is dropped in the slot 30 it will fall into the groove 26 with a portion remaining in the notch 34, then when the handle 36 is moved in the direction of the arrow, Fig. 2, the coin will be moved around the groove 26 and carry the ring plate or cover 33 with it until the coin reaches the slot 31 where it will drop into the machine. This movement of the ring plate or cover will bring the hole 35 therein into registration with the hole 29 in the top so that an empty container may be inserted. After this is done the ring plate or cover may be returned to its normal closed position by reversing the movement of the operating handle causing the finger 37 to move the cover in the reverse direction by reason of its engagement with the lip 38.

In order to lock the operating handle and shaft a keeper 39 may be pivoted to the top 27 in the region of the slot 30. The free end of such keeper is provided with a nose 40 for insertion in a hole in the end of the finger 37 and also has a tongue 41 with a beveled upper surface to project across the slot 30. The keeper is normally forced in-

ward by a spring 42. As a coin is inserted in the slot 30 it will engage the tongue 41 and force the keeper outward against the action of the spring 42 and disengage the nose 40 from the finger 37 releasing the actuating shaft for movement in the first step of the vending operation.

Fixed to the central tube or hollow column 22 are other supports, here shown as two in number, the one directly above the support 15 being represented by the numeral 43 and the one above the support 43 designated by the reference 44. Each of these has a hub 45 and a concentric rim or flange 46 providing a raceway and through the support 43 within the raceway is a hole 47, Figs. 11 and 12, in staggered relation to the hole 19 in the support 15 as may be ascertained by reference to Figs. 11 and 13 which are in proper relative positions to each other the same as when the machine is completely assembled. Through the support 44 within its raceway is formed a hole 48, Figs. 9 and 10, staggered relative to the hole in the support 43 but in a direct straight line with the hole 19 in the bottom support 15, likewise the hole 29 in the top 27 is in staggered relation to the hole 48 in the uppermost support 44 but in a direct straight line with the hole 47 in the intermediate support 43.

In the raceways of the supports 15, 43 and 44 are slidably or revolvably mounted the carriers 49, 50 and 51 respectively, each including an annulus 52 and a plurality of circular partitions 53 providing chambers for the reception of suitable containers or "bottles."

The revolving of the carriers is accomplished through the medium of the containers or "bottles" in conjunction with the compound levers 54, 55 and 56. Each compound lever comprises a forked member 57 fixed to the operating shaft 21 and having a pair of spaced horns 58 between which is located and adapted to work a pin 59 carried by the other member 60 loosely journaled on the operating shaft 21 and coacting with the forked member. The member 60 of lever 55 is reverse to that of the other levers. Said other member 60 is adapted to project through a slot 61 in the tube or hollow column 22 below the partitions 53 of a carrier so as to engage a container or "bottle" in said carrier.

The member 60 of the compound lever 56 may be locked in one position by means of a bolt 62 which is slidably mounted in the housing 63 fixed to the central tube or hollow column 22 and adapted to assume its locking position by gravity. The toe 64 of said bolt registers with a cavity 65 in the member 60 of the compound lever 56 while the head 66 of said bolt has a beveled under surface for coaction with the inclined upper surface 67 of the lock bolt actuating arm

68 journaled on the operating shaft 21 between two nuts 69 or their equivalent having threaded connection with a portion of the operating shaft. The nuts frictionally engage the arm 68 to cause it to rotate with the shaft under certain conditions while permitting it to be readily actuated independently of the shaft when occasion requires.

When the machine is operated upon the insertion of a coin as above described the hole 35 in the ring plate or cover will be in alignment with the hole 29 in the top while the member 60 of the compound levers 54 and 56 will be in the positions shown by dotted lines in Fig. 6 and therefore to the rear of the holes 29 and 47 above them. As soon as a container or "bottle" is inserted in the hole 29 it will engage the outer end of the arm 68 and move it over sufficiently to cause the bevel upper surface thereof to lift the bolt 62 and disengage its toe 64 from the cavity 65 in the member 60 of the uppermost compound lever 56 permitting the operating handle 36 to be returned to its normal position, the movement of which is approximately seventy-five degrees, while moving the members 60 of the compound levers but thirty-six degrees. This movement of the compound levers will force the carriers 49 and 51 in the same direction as the movement of the operating handle through the engagement of the compound levers with one of the containers or "bottles" in the respective carriers.

When this movement of the carriers is completed a container traveling on the support 44 by the carrier 51 will drop through the hole 48 in said support on to the next succeeding support 43 entering an empty chamber in the carrier forward of the hole 47 in the support 43, so that the container dropping onto the support 43 will be on the left hand side of the lever 55 when the latter is in the position shown in Fig. 7. As the operating handle is again moved in the direction of the arrow in Fig. 2, the member 60 of lever 55 will move the carrier on the support 43 in a direction opposite that of the carriers 49 and 51.

Upon insertion of another coin for the next operation of the machine the handle will be given its first movement to open the machine and this will cause the member 60 of the compound lever 55 to engage the container which has dropped from the support 44 to the support 43 and move all of the containers on said support 43 forward one stop thus causing a container to pass through the hole 47 in the support 43 and drop into an empty chamber in the carrier 49 associated with the support 15. As this movement is completed the member 60 of the compound lever 56 will be locked by the bolt 62 and will remain locked until the container is inserted through the hole in

the top for again actuating the arm 68 to move the bolt to an unlocked position. As soon as this is done and the operating handle 36 again returned to its normal position the containers in the lowermost carrier 49 will be moved until one of them drop through the exit 19 and as said container is delivered to the customer a container of the uppermost carrier 51 will drop through the hole 48 in the support 44 into an empty chamber 75 in the carrier 50 on the support 43.

From the foregoing it will be seen that it is necessary that both a coin and a container must be inserted in the machine before the complete vending operation can take place for the delivery of a full container at the bottom of the machine.

Of course I do not wish to be limited to the exact details of construction as herein shown as these may be varied within the limits of the appended claims without departing from the spirit of my invention.

Having thus fully described my invention, what I claim as new and useful is:

1. A machine for vending merchandise in returnable containers comprising a plurality of supports arranged above one another each having a single communication with the support beneath, the communication between alternate supports being in staggered relation, and means to move containers resting on the supports toward the communications between supports, said means being placed in operative condition by the insertion of a coin and a container in the machine.

2. A machine for vending merchandise in returnable containers comprising a plurality of supports arranged above one another each having a single communication with the support beneath, the communication between alternate supports being in staggered relation, and means to move containers resting on the supports toward the communications between supports, said means being movable one step upon insertion of a coin and movable a second step after the first movement by the insertion of a container.

3. A machine for vending merchandise in returnable containers comprising a plurality of supports arranged above one another each having a single communication with the support beneath, the communication between alternate supports being in staggered relation, rotatable means associated with each support to hold containers for moving them in unison, mechanism operable from the exterior of the machine and coacting with a container of each group to move said containers toward the point of communication with the support below, coin controlled means to lock said mechanism and means controlled by a returnable container to lock said mechanism in a semi-open condition.

4. A machine for vending merchandise in

- returnable containers which will insure the return of an empty container as well as the depositing of a coin to secure a full container, such machine comprising a plurality of fixed supports, each having a hole to permit a container to drop from one support to the one beneath and means controlled by a coin and a container to move the containers over the supports toward the holes.
10. 5. A machine for vending merchandise in returnable containers which will insure the return of an empty container as well as the depositing of a coin to secure a full container, such machine comprising a plurality of fixed supports arranged above one another, each having a hole to permit a container to drop from one support to the one beneath, the holes in alternate supports being in staggered relation, carriers associated with each support to hold the containers in upright positions and move them in unison over the supports, alternate carriers adapted to be rotated in opposite directions, a hollow column, a ring having a groove therein mounted on the upper end of the column, said ring further having a coin slot leading from the groove, a top provided with a coin slot in staggered relation to the first named coin slot and having a hole in staggered relation to the hole in the uppermost support, a rotatable ring plate beneath the top and provided with a hole adapted to be moved into alignment with the hole in the top and further provided with a coin notch, an operating shaft enclosed within the column and projecting through the top, a handle on said projecting end, a finger fixed to the shaft for engagement with a coin lying in the groove of the ring and the notch in the ring plate whereby the latter may be rotated in one direction, means on the ring plate for coaction with said finger for moving the ring plate in the other direction, coin actuated means to lock the finger and component parts when the machine is closed, compound levers each comprising a forked member fixed to the shaft, another member journaled on the shaft and a pin carried by said other member for co-operation with the forked member, said other member of each compound lever projecting through the hollow column for coaction with a container on each support for propelling all the containers on the supports toward the holes therein.
30. 6. A machine for vending merchandise in returnable containers which will insure the return of an empty container as well as the depositing of a coin to secure a full container, such machine comprising a plurality of fixed supports arranged above one another, each having a hole to permit a container to drop from one support to the one beneath, the holes in alternate supports being in staggered relation, carriers associated with each support to hold the containers in upright positions and move them in unison over the supports, alternate carriers adapted to be rotated in opposite directions, a top having a hole therethrough in staggered relation to the hole in the uppermost support, a ring plate having a hole therethrough and rotatable to align the hole therein with the hole in the top, an operating shaft having an end projecting through the cover, a handle on said end and compound levers connected with the operating shaft and adapted to engage a container on each support for propelling all the containers on the supports toward the holes therein.
40. 7. A machine for vending merchandise in

returnable containers which will insure the return of an empty container as well as the depositing of a coin to secure a full container, such machine comprising a plurality of fixed supports arranged above one another, each having a hole to permit a container to drop from one support to the one beneath, the holes in alternate supports being in staggered relation, carriers associated with each support to hold the containers in upright positions and move them in unison over the supports, alternate carriers adapted to be rotated in opposite directions, a hollow column, a ring having a groove therein mounted on the upper end of the column, said ring further having a coin slot leading from the groove, a top provided with a coin slot in staggered relation to the first named coin slot and having a hole in staggered relation to the hole in the uppermost support, a rotatable ring plate beneath the top and provided with a hole adapted to be moved into alignment with the hole in the top and further provided with a coin notch, an operating shaft enclosed within the column and projecting through the top, a handle on said projecting end, a finger fixed to the shaft for engagement with a coin lying in the groove of the ring and the notch in the ring plate whereby the latter may be rotated in one direction, means on the ring plate for coaction with said finger for moving the ring plate in the other direction, coin actuated means to lock the finger and component parts when the machine is closed, compound levers each comprising a forked member fixed to the shaft, another member journaled on the shaft and a pin carried by said other member for co-operation with the forked member, said other member of each compound lever projecting through the hollow column for coaction with a container on each support for propelling all the containers on the supports toward the holes therein, means coacting with one of the compound levers to lock it and the component parts in a semi-opening position and means actuated by the insertion of an empty container in the top hole for releasing the last named locking means.

In testimony whereof, I have hereunto affixed my signature.

JOHN E. CARROLL.
